UNITED STATES PATENT OFFICE.

WILLIAM MCAUSLAND, OF TAUNTON, MASSACHUSETTS, ASSIGNOR TO THE REED & BARTON CORPORATION, OF SAME PLACE.

DESIGN FOR A SPOON.

SPECIFICATION forming part of Design No. 31,461, dated August 29, 1899.

Application filed August 4, 1899. Serial No. 726,200. Term of patent 14 years.

To all whom it may concern:

Be it known that I, WILLIAM MCAUSLAND, a citizen of the United States, residing at Taunton, in the county of Bristol and State of Massachusetts, have invented and produced a new and original Design for a Spoon, of which the following is a specification, reference being had to the accompanying drawings, forming part thereof, and in which—
10 Figure 1 is a side view, and Fig. 2 is a bottom plan view, of a spoon, showing my new design.

The leading or material feature of my design consists in the design forming the subject-matter of the accompanying illustration.
15 As shown in the drawings, the handle A is

returned or bent downward at A', the portion below such bend A' being bent or curved reversely, simulating the line of beauty.

Having thus described my invention, what I claim, and desire to secure by Letters Patent, is—

The design for a spoon as herein shown and described.

In testimony whereof I have signed my name to this specification in the presence of two subscribing witnesses.

WILLIAM MCAUSLAND.
